D. C. KLAUSMEYER

CHANGE GEAR

Original Filed Aug. 25, 1920

UNITED STATES PATENT OFFICE.

DAVID C. KLAUSMEYER, OF CINCINNATI, OHIO, ASSIGNOR TO THE CINCINNATI BICKFORD TOOL COMPANY, OF OAKLEY, CINCINNATI, OHIO, A CORPORATION OF OHIO.

CHANGE GEAR.

Original application filed August 25, 1920, Serial No. 406,009. Divided and this application filed January 3, 1924. Serial No. 684,155.

To all whom it may concern:

Be it known that I, DAVID C. KLAUSMEYER, a citizen of the United States, and residing at Cincinnati, in the county of Hamilton and 5 State of Ohio, have invented new and Improved Change Gears, of which the following specification is a full disclosure.

This invention relates to so-called change gears wherein different gear ratios are 10 brought into serial relation to yield any one of a predetermined number of speeds; this application being a division of my co-pending application Ser. No. 406,009 filed August 25, 1920.

15 An object of the invention is to devise a speed-change system of a very simple, compact nature appropriate for various types of machine tools and especially for power drills.

20 Other objects and advantages will be in part indicated in the following description and in part rendered apparent therefrom in connection with the annexed drawings.

To enable others skilled in the art so fully 25 to apprehend the underlying features hereof that they may embody the same in the various ways contemplated by this invention, drawings depicting a preferred typical construction have been annexed as a part of 30 this disclosure and, in such drawings, like characters of reference denote corresponding parts throughout all the views, of which:

Fig. 1 is a side elevation of a gear box embodying this invention. Fig. 2 is a sectional 35 development thereof showing the relations between the respective gears and illustrating certain details of the gear shaft instrumentality. Figs. 3 and 4 are detail sectional views showing the means for shifting the 40 gear-units later to be referred to. Fig. 5 is a diagrammatic representation of the flow of motion in this feed-change mechanism.

Turning now to Fig. 5, the scheme of transmission will be understood. The power 45 is transmitted from p , the prime-mover, along the main-line transmission $p-a-b$ to the junction b where it takes either branch-line $b-c$ or $b-c'$, depending upon whether the clutch (which in this case assumes the 50 form of a shifting gear) establishes connection between the terminals c and d or the terminals c' and d' . The power then is transmitted from d or d' (as the case may

be) to either of the terminals e , e' , e'' or e''' , depending upon which of the gaps $e-f$, $e'-f'$, $e''-f''$ or $e'''-f'''$ are closed by an appropriate clutch-operation, such, for example, as a gear-shift. From such terminals, the power is transmitted to g and then to h where it is utilized. This arrangement affords to gear ratios $b-c-d-x$ and $b-c'-d'-x$ either of which may be arranged in series with any one of the four different gear ratios $x-e-f-g$, $x-e'-f'-g$, etc; thereby yielding eight different speeds. Since the branch-line transmissions have different individual ratios, it will be seen that not more than one of the gaps $e-d$ and $e'-d'$ may be closed simultaneously, and likewise but one of the gaps $e-f$, $e'-f'$, etc., may be closed during the same period. Furthermore, the general system should not be transmitting power (i. e., gap $g-a$ should be open) when the clutch-operations are being performed otherwise parts would be injured. Hence, in the structural embodiment of this scheme, a novel interlocking instrumentality is resorted to to safeguard against this contingency. This will now be explained in detail.

Referring now to Fig. 1, a suitable casing A provides journals for a power shaft X, an intermediate shaft Y and a delivery shaft Z. Shiftably splined to the shaft X is a gear couplet C providing two gears c^1 and c^2 . Keyed to the intermediate shaft Y are two gears d^1 and d^2 ratioed differently and adapted to be brought into mesh with the aforesaid gears c^1 and c^2 ; there being on this shaft also gears e^1 , e^2 and e^4 . On the delivery shaft Z there are two shiftable gear couplets F and F' providing gears f^1 , f^2 , f^3 and f^4 which, by shifting of the appropriate gear couplet, F or F', may be brought into mesh with the respective one of the four above-mentioned gears. These gears are differently ratioed so that this arrangement provides eight different ratios between the driving and the driven shaft.

A prime-mover, here instanced as a pulley B, is arranged adjacent the shaft X and may be connected therewith by means of a suitable clutch, such as the friction clutch D, which provides an expandible shoe q adapted to be forced into an engagement with the surface p of the pulley B, by the wedge-ac-

tion of a taper bar 1 controlled in position by the shiftable collar 2. A construction suitable for this purpose is exemplified, for example, by the patent to Norris No. 5 1,030,424.

The position of the shiftable collar 2 is determined by means of a yoke 3 secured to a rod 4 which translates in bearings 5 and 6 and is actuated by means of a lever 7 having an operating handle 8 and terminating in an arm 9 having a suitable connection with the rod 4 as, for example, by means of the tongue and groove connection 10. The rod 4 has a portion 11 extending into the bearing 6 and provided with two notches 12 and 13 into which the wedge-shaped end of two locking pins 14 and 15 may enter. It will be seen that, by virtue of the wedge-shaped extremities of the pins 14 and 15, the rod 4 can freely translate when these pins are in the notches 12 and 13 only in case there is nothing to prevent the pins 14 and 15 from freely moving longitudinally. As will subsequently appear, such longitudinal movement is prohibited under certain conditions by the levers that control the shifting of the gears. That is to say, it is only after the gear-shift levers have been moved to establish an appropriate meshing relation 30 between the different gears, that it is possible to translate the rod 4 and connect the power with the gearing. The converse is also true that, after the rod 4 has been shifted to connect the power with the gearing, it becomes impossible to move either of the gear-shift levers and, if it be desired to change the gear ratio, the power lever 7 will have to be first restored to its inoperative position.

A single lever K controls the position of the gear couplet C. This lever (see Figs. 1 and 3) is secured to a shaft 16 journaled in a bearing 17 and having connected to its inner end an arm 18 the end of which pivotally carries a shoe 19 that rides between the gears c^1 and c^2 , and determines the position of the gear couplet in accordance with the angular position of the lever K which is moved by the handled portion K'. The hub 50 of the lever K carries a notched segment M provided with two notches m^1 and m^2 which will be in registry with the upper tapered extremity of the pin 15, when the corresponding gears c^1 and c^2 are in engagement. It will be seen that, in this condition of registry, the pin 15 is free to translate, and therefore does not lock the rod 4. Likewise when the lever K is in the intermediate position shown by Fig. 1, the periphery of 60 the segment M interferes with any translation of the pin 15, and consequently the rod 4 cannot be moved. So also, whenever the power is on, the pin 15 will be seated in either one or the other of the notches m^1 and 65 m^2 and therefore it is necessary to move the

rod 4 until the pin 15 can enter the notch 13 before it is possible to swing the lever K.

A single lever has also been devised and arranged so as to enable it to move either one or the other (but not both simultaneously) of the gear couplets F and F' into the appropriate tooth engagement. This is achieved as follows: From the right and the left side of the casing A project two square studs 20 and 21 and on these ride 70 the yokes or gear shifters G and G'. These yokes embrace the ends of the gear couplets F and F', respectively, thereby enabling the gears to be located close together. These yokes are impositively retained in 80 either one of their two operative, or in their inoperative, positions by means of spring-pressed plungers 14' and 15'. These yokes are provided with oppositely extending arms 22 and 23 having vertical slots 24 and 85 25 which lie directly opposite or in registry whenever the yokes G and G' are in neutral position. A lever mechanism is provided which, alternately, can engage the one or the other of said slots 23 and 24 and remains 90 in that engagement for the purpose of shifting the corresponding yoke either to the right or to the left, and continues in that engagement as a matter of necessity so long as the yoke is in any other than 95 its neutral position. A shaft 26 extends from the outside through the wall of the casing A and at its inner end securely carries a depending arm 27. This shaft 26 is both rotatable and translatable in the 100 bearing 28. At its lower end, the arm 27 pivotally carries a pin 29 which is restrained against translation by means of a collar 30 located within the slot 31 provided by the depending arm 27. The ends 105 of the pin terminate in tongues 34 and 35, and the pin is of such length that, when the tongue 35 is inserted in the slot 25, its other end will entirely clear the slot 24, and conversely. It is also of such length that it 110 cannot be moved entirely out of one slot before it begins to enter the other slot, thereby insuring that the yokes G and G' are both in neutral position when the depending arm 27 is being transferred from 115 its operative connection with the one yoke to its operative connection with the other yoke. This transference is achieved by effecting a translation of the shaft 26 and, after that has been done, a rotation or oscillation of the shaft 26 effects a shift of the engaged yoke and establishes the desired gear intermesh. To translate and oscillate the shaft 26, a hand operated lever R is employed. This lever has no fixed pivot but has a floating pivot 36 whereby it is attached to the outer end of the shaft 26, as is shown more clearly by Figs. 1 and 4. This lever R is fulcrumed at all times about a ball T constituting the upper extremity 120 125 130

of the shiftable pin 14. This fulcrum is maintained in all angular positions of the lever R by means of side plates S with which the lower end of the lever R is provided. Between these side plates S is a circular segment s provided with two spherical seats s^1 and s^2 adapted to receive the ball T when the pin 14 has been thrust upwardly by virtue of the translation of the rod 4, as explained in connection with the pin 15. This arrangement prevents the lever R from being oscillated so as to rotate the shaft 26 when the power is on. In order to further control and assist the lever R in its various movements, its shank r passes through an H-plate N which is provided with four slots n^1 , n^2 , n^3 and n^4 with a communicating central slot. This central slot corresponds to the neutral position of the two yokes G and G' and therefore the H-plate permits the lever R to be shifted so as to translate the shaft 26 only when the parts are in neutral position. When the lever is shifted back or forth within the plane of the slots n^1 and n^2 , it is actuating the yoke G and the gear couplet F, but when it is swung in the plane of the slots n^3 and n^4 , it is shifting the yoke G' and the gear couplet F'. It will therefore be apparent that the lever R can engage only one of the four gears controlled by it at any one time.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. A speed-change mechanism combining only five gears keyed to an intermediate shaft; two gears on a power shaft, the one being adapted to be engaged with one of said five gears, and the other with another of said five gears, four gears splined on a delivery shaft, two of said gears being engageable with two of the five gears on the intermediate shaft not engaged by either of the gears on the power shaft, and the remaining two of the gears on the delivery

shaft being respectively engageable with one or another of the remaining gears of the intermediate shaft; and hand-controlled means for effecting said engagement. 65

2. An intermediate shaft containing a first, a second, a third, a fourth and a fifth gear; a first shaft mounting two gears, the one being engageable with the third gear and the other being engageable with the 70 fourth gear; a third shaft; two gears slideable thereon, the one being engageable with the first gear and the other with the second gear; two more gears slideable on said third shaft, the one being engageable with the 75 fourth gear and the other with the fifth gear; and a manually controlled means for shifting said gears.

3. A speed-change mechanism combining three parallel shafts viz. a power shaft, an intermediate shaft, and a delivery shaft only; two integrally formed gears translatable secured to said power shaft; five independent gears fixedly secured to said intermediate shaft only; two pairs of integrally formed gears translatable secured to said delivery shaft, one of the gears on said intermediate shaft being engageable by one of said gears on each of the power and delivery shafts and each of the other gears on the intermediate shaft being engageable by only one of said other gears; and manually controlled means for shifting the gears on said power and delivery shafts. 80

4. A speed-change mechanism combining a power shaft; an intermediate shaft; a delivery shaft; an even number of gears translatable secured to said power shaft; an uneven number of gears secured upon said intermediate shaft; an even number of gears secured to said delivery shaft, said last named gears being greater in number than the gears on said power shaft; manually controlled means for selectively effecting an operative connection between either of the 95 gears on said power shaft and either of two of the gears on said intermediate shaft; and manually controlled means for selectively connecting any one of the gears on said delivery shaft with certain of the gears on 100 said intermediate shaft, one of the gears on said intermediate shaft being adapted to mesh with a gear on each of said power and delivery shafts. 105

In witness whereof, I hereunto subscribe 110 my name, as attested by the two subscribing witnesses.

DAVID C. KLAUSMEYER.
